United States Patent Office

Des. 184,915
Patented Apr. 21, 1959

184,915

KITCHEN POWER UNIT OR SIMILAR ARTICLE

Peter W. Cherry, Monroe, and Alfred W. Wakeman,
Newtown, Conn., assignors to The A. C. Gilbert Company, New Haven, Conn., a corporation of Maryland

Application December 2, 1957, Serial No. 48,744

Term of patent 14 years

(Cl. D26—5)

Fig. 1

Fig. 2

Fig. 1 is a top plan view of a kitchen power unit or similar article, showing our new design;

Fig. 2 is a front elevational view;

Fig. 3 is a rear elevational view;

Fig. 4 is a side elevational view;

Fig. 5 is an opposite side elevational view thereof.

We claim:

The ornamental design for a kitchen power unit or similar article, substantially as shown.
